UNITED STATES PATENT OFFICE.

JAMES R. WRIGHT, OF DENVER, COLORADO.

VAPOR-BATH CABINET.

1,231,466.

Specification of Letters Patent. Patented June 26, 1917.

Application filed October 19, 1914. Serial No. 867,357.

To all whom it may concern:

Be it known that I, JAMES R. WRIGHT, a citizen of the United States, residing in the city and county of Denver and State of Colorado, have invented certain new and useful Improvements in Vapor-Bath Cabinets; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in vapor bath cabinets, my object being to provide a construction possessing a number of features of novelty and a number of advantages over other so-called cabinets intended to accomplish a similar object. In my improvement, the body member is approximately cylindrical in shape, and the cover or lid is circularly slidable when open and in parallel relation with one side of the casing, thus concealing the lid. The cabinet is further provided on one side with a hinged longitudinally disposed door which is normally held in the closed position by means of spring clips arranged at the opposite ends of the structure, but is adapted to be swung downwardly in order to allow the patient to readily enter or leave the cabinet. By virtue of this peculiar design of cabinet, the latter occupies comparatively little space and it may be located in the middle of a room or in any other desired locality.

Another novel feature of the construction consists of a head rest having two adjustments, namely, a vertical adjustment whereby the entire head rest structure may be moved up or down at will; and a pivotal adjustment whereby the head rest proper may be adjusted upon the holder in order to get an inclination suitable to conform to the comfort of the patient. In the lower part of the cabinet below the platform upon which the patient reclines during the treatment, is located a perforated pipe composed of a number of sections readily separable. One of these sections is directly connected with the gas heater which vaporizes the liquid preparation to which the body of the patient is subjected while taking the bath. This section naturally is subjected to much greater heat than the sections far-

ther removed from the heater, and consequently, will become worn, due to the excessive heat and will require replacement more often than the other sections farther removed from the heat source. Hence, by this additional construction of the perforated pipe or tube, the entire tube need not be discarded when the portion in close proximity to the heater must be removed.

Having briefly outlined my improvement, I will proceed to describe the same in detail, reference being made to the accompanying drawing, in which is illustrated an embodiment thereof. In this drawing,

Fig. 1 is a side elevation of my improved vapor bath cabinet, showing the top lid of the side door open. This view is taken looking in the direction of arrow 1, Fig. 3.

Fig. 2 is a vertical longitudinal section taken approximately on the line 2—2, Fig. 4, showing the top lid and the side door both closed.

Fig. 3 is a closed section taken on the line 3—3, Fig. 1, looking toward the left.

Fig. 4 is a section taken on the line 4—4, Fig. 2, looking toward the right.

The same reference characters indicate the same parts in all the views.

Let the numeral 5 designate a casing approximately cylindrical in shape. The rear portion of this casing merges into parallel vertically disposed side parts 6, which at their lower extremities in turn merge into 90 downwardly inclined members 7, which in connection with similarly inclined end parts 8, constitute a sort of hopper-shaped bottom which facilitates the removal of the liquid resulting from vapor condensed in the 95 cabinet. Leading downwardly from the center of this hopper-shaped lower portion of the casing, is a drain pipe 9, which may be connected with the sewer. The upper cylindrical part of the casing is provided 100 with a top lid or cover 10, which is curved to conform to the curve of the rear side wall 12 of the casing, and is adapted to slide into engagement therewith when the lid is open (see Figs. 1 and 3). This lid 105 is equipped at its forward extremity with an end member 13 which partly closes the front end of the cabinet. The inner edge 16 of this member 13 is provided with an outwardly projecting flange 14, which 110 engages a similar flange 15 formed upon the stationary end member, and acting as a

guide to the lid during its sliding movement as it is opened and closed. The flange 15 forms a bearing for the forward extremity of the slideable lid while the opposite extremity of the latter is equipped with a V-shaped support 17 whose two arms 18 are secured at their outer extremities to the curved portion of the lid, as shown at 19. The inner extremity of this V-shaped member is pivotally connected with the rear end wall of the casing, as shown at 20. The outer edge of the end wall 21 has an inwardly projecting flange 22 which forms a guide for the rear extremity of the lid and the latter is thus maintained in operative relation with the casing, and secured against longitudinal movement in a rearward direction (see Fig. 2).

The end member 13 of the lid is provided with a rod 23, the extremities of the rod being secured to the part 13, while its body portion is offset therefrom (see Figs. 1 and 2), whereby the rod is adapted to hold a towel. This rod is so positioned that during the operation of taking the bath, the towel, which is supported by the rod, hangs downwardly and engages the neck of the patient, thus preventing the heat from the interior of the cabinet from passing to the face and head of the patient.

The lid 10 is further provided with an opening 24 which is adapted to be closed by an interiorly located slide 25 whose edge engages offset guides 26 which form grooved ways for the opposite edges of the slide, the latter being provided with an exteriorly located projection 27, to facilitate its manipulation. By moving this slide to the open position, the temperature within the cabinet may be reduced if it should become too hot. Again, by moving the slide to the open position, the patient may be treated by the use of a shower or spray, as may be desired.

The free, longitudinal edge of the lid 10 is provided with an outwardly projecting flange 28 while the end part 13 is provided with an exteriorly projecting flange 29 which rests upon a shoulder 30 formed upon the front end of the casing, which is reinforced by an interior plate 31, thus giving this part of the casing a thickness equal to the thickness of the interiorly projecting guide flange 15. This reinforcement 31 gives additional strength and stability to the structure.

The casing is further provided on one side with a door 32 hinged at 33 and normally held in the closed position by a pair of spring clips 34 which are secured to the opposite end walls of the casing. The free, longitudinal edge of this door is equipped with an outwardly projecting flange 35, which, when the door is closed, abuts against the flange 28 of the lid 10. The longitudinal edge of this door 32 is equipped slightly above the

hinge when the door is in the closed position, with a rib 36, which, when the door is in the open position, is located at the lower part of the side opening which the door closes. This rib forms a rounded bearing for the limbs of the patient as he leaves the cabinet, thus preventing the annoyance which would attend the engagement of the limbs with the relatively thin edge of the door which would otherwise exist. When the door is in the open position, this rib or rounded part 36 extends slightly above the hinge 33 of the door, and thus forms a comfortable support for the body while leaving or entering the cabinet. This rib 36 also forms a seal to prevent the escape of liquid.

Adjacent the flange 28, located along the free longitudinal edge of the lid as heretofore explained, is positioned an exteriorly projecting hand piece 37, which is suitably secured to the lid as by riveting the inner extremities of this hand piece on the inside of the lid after they have been passed through openings formed therein for the purpose.

Within the cabinet and located near the bottom of the cylindrically curved walls thereof, is a platform 38 upon which the body of the patient rests while taking the bath. As illustrated in the drawing, this platform is composed of a series of slats or relatively narrow pieces of wood or other suitable material 39 which are suitably spaced as shown at 40, and connected by a number of transversely arranged ribs 41, which, as illustrated in the drawing, are composed of metal, the rib members being formed of two thicknesses bent to engage each other, the ribs having flanges 42 extending in both directions from the body of the rib, the flanges being secured to the slats or members 39 by suitable fastening devices. These ribs may be composed of copper, aluminum, or other suitable metal that will not corrode or be injuriously affected by the action of the sulfur or other vaporized chemicals employed in treating the patient. This platform is supported by a rod 43 whose opposite extremities are fast in the end walls of the cabinet and suitably spaced from the curved wall oppositely located from the door 32, whereby the platform may be raised to the position shown by dotted lines in Fig. 3 and supported by the rod in such raised position during the cleaning of the cabinet.

As the platform is raised as stated, its free edge 44 moves downwardly below the rod and supports it in the raised position, as will be understood. The edge 45 of the platform or that adjacent the door 32 when the parts are in position for use, is supported by exteriorly projecting angle members 46.

Below the platform 38 is located and suitably supported, a perforated pipe 47, which

is centrally located and longitudinally disposed in the cabinet. As illustrated in the drawing, the forward extremity of this pipe engages a supporting bracket 48, while the 5 opposite extremity is provided with a short depending member 49 which enters a pipe member 50 which extends upwardly into the cabinet and also exteriorly thereof, as shown at 51. The lower extremity of the part 51 10 extends outwardly as shown at 52, forming a sort of inverted funnel and constituting the upper portion of the heater 53, whose lower or body portion 54 contains liquid 55 to be vaporized. Underneath the bottom of 15 the part 54 is located a burner 56, which is supplied with fuel, as gas, through a conduit 57, controlled by a valve 4.

The pipe 47 as illustrated in the drawing, is composed of three sections, respectively 20 designated 58, 59 and 60. The part 58 is provided with the short depending member 49, which enters the upwardly projecting tubular part of the heater, as heretofore explained. The part 60 is forwardly located, 25 the forward extremity resting directly upon the bracket 48; while the extremities of the section 59 respectively enter the adjacent extremities of the two sections 58 and 60. In this manner, the three sections of the pipe 30 are held in the assembled relation. The opposite extremities of this pipe or the outer ends of the sections 58 and 60, are provided with closures or caps 61. The lower portion of this pipe 47 is perforated below its horizontal 35 diameter as shown at 62. As illustrated in the drawing, a number of longitudinally disposed rows of perforations are formed. By reason of these perforations, vapor is discharged downwardly from the 40 pipe and directed into the lower portion of the cabinet, and rises upwardly on opposite sides following the inner curved surfaces of the cabinet, the two currents meeting at the top and being directed downwardly upon the 45 patient. In this way, the latter is subjected to the best possible influence.

As illustrated in the drawing, the heater is supported in a cage or skeleton frame work 63, which is secured to the bottom of 50 the casing and suspended therefrom. This structure is such that the heater may be readily removed and placed in position during the setting up and taking down of the cabinet.

55 Exteriorly applied to the forward extremity of the structure, is a head rest 64, which consists of a supporting arm 65 and a head rest member 66. This arm 65 is slidably connected with a stationary arm 67, rigidly secured exteriorly to the forward lower part of the cabinet, as shown at 68, by means of a set bolt 69, which is fitted in an opening in the arm 65 and passes through a slot 89 formed in the part 67. The upper 60 portion of the arm 65 is bent outwardly

and channeled as shown at 70, the side flanges 71 being perforated to receive a set bolt 72 which also passes through a registering opening formed in a depending lug or ear 73 which is secured to the bottom 70 of the head rest as shown at 74.

The upper surface of this head rest is suitably upholstered and its extremity adjacent the cabinet is provided with a short depending open-ended tube 75, through which 75 perspiration or other liquid which may be applied to the head or face of the patient, may pass and enter a tube 76 whose outer extremity is suitably flared for the purpose. This tube 76 passes through an opening in 80 the lower front end wall of the cabinet and projects slightly thereinto for drainage purposes, as shown at 77. The threaded extremities of the set bolts 69 and 72 are provided with winged nuts 78 and 79. By 85 loosening the nut 78, the head rest may be raised and lowered bodily, while by loosening the nut 79, the head rest may be turned on the bolt 72 as a pivot, whereby any desired inclination of the head rest may be 90 obtained, according to the wish or comfort of the patient.

From the foregoing description, the use and operation of my improved vapor bath cabinet will be readily understood. Assuming that the lid 10 of the door 32 is open, (see Figs. 1 and 3), the patient enters the cabinet and reclines upon the platform 38 with his head engaging the head rest member 66. In this event, the neck of the patient occupies the lower portion of the opening 80 in the forward end of the cabinet. The wall of this opening, when the lid 10 is in the open position, is free in the top to allow the neck of the patient to pass freely 100 therethrough. Assuming that the body of the patient is positioned as just described, the lid 10 of the door 32 will be closed (see Figs. 2 and 4). Before closing the lid 10, a towel 81 is placed upon the rod 23 and 105 when the lid is closed, this towel engages the neck of the patient on the inside of the cabinet, and thus guards the face and head from the heat or vapor which otherwise would come in contact therewith. This 110 towel may be dampened or wet according to the desire or comfort of the patient. As soon as the cabinet is closed, the burner 56 is lighted and through the instrumentality of the heater, the liquid 55 is vaporized, the 115 temperature within the cabinet at the same time being raised to such an extent as to produce free perspiration at the same time that the medicated vapors are brought in contact with the body, thus producing a double 120 therapeutic effect, namely, that due to the perspiration, whereby the impurities are discharged from the body; and the influence of the medical properties of the vaporized liquid which enter the pores of the body which 125 130

are in condition therefor due to the free perspiration. Other treatment, as by spraying the body by the use of a conduit passed through the opening 24, may be employed, if desired at any stage of the treatment.

Having thus described my invention, what I claim is.—

1. A bath cabinet comprising a casing and a platform located therein, a rod fixed at the ends of the casing and forming a support for the platform near one edge thereof, whereby when the opposite edge of the platform is raised, the edge nearer the rod will move downwardly between the rod and the adjacent wall of the casing, whereby the rod will support the platform in the raised position.
2. A bath cabinet comprising a casing and

a platform located therein, a rod fixed at the end of the casing and forming a support for the platform near one edge thereof, whereby, when the opposite edge of the platform is raised, the edge nearer the rod will move downwardly between the rod and the adjacent wall of the casing, whereby the rod will support the platform in the raised position, the casing being provided with a support for the edge of the platform remote from the rod, substantially as described.

In testimony whereof I affix my signature in presence of two witnesses.

JAMES R. WRIGHT.
